HOLLOW DISPLAY ARTICLE

Richard H. Erlewine, Marion, Ind., assignor to
General Plastics Corporation, Marion, Ind., a
corporation

Application April 22, 1948, Serial No. 22,552

2 Claims. (Cl. 240—10)

1

This invention relates to hollow display articles such as decorative signs, Christmas ornaments, and the like capable of being illuminated, display forms for clothing, and similar three dimension structures formed of sheet material.

It is the purpose of the invention to provide a light and economical structure of the above character such as may serve as illuminated outdoor Christmas ornaments and displays having a pleasing and attractive appearance and capable of being packed and shipped in knockdown form or sections and conveniently assembled.

The invention contemplates an assembly of opposed and mating sections of thermoplastic sheet material of a cellulose derivative, each section being preformed to a surface contour such as when assembled presents a decorative three dimension article. Such structure permits the sections to be disassembled for nesting and packing, and conveniently assembled after shipment.

Another feature of the invention resides in forming a surface illuminated article formed of a pair of opposed and mating sections of translucent sheet material such as when the sections are assembled they may embrace a centrally disposed lamp bulb, and providing reflective and light diffusing surfaces in a manner to distribute and diffuse light throughout the entire structure. For example, when the article takes the form of a holly wreath surrounding a Christmas bell or similar decorative figures, the light rays emitting from a lamp contained within the bell will be directed about and diffused from the surface of the surrounding wreath.

The full nature of the invention will be understood from the accompanying drawings and the following description and claims:

Fig. 1 is a front elevation of one form of an illuminated decorative article simulating an annular holly wreath surrounding a Christmas bell for illumination from a centrally disposed light source.

Fig. 2 is a section taken on the line 2—2 of Fig. 1.

Fig. 3 is a section taken on the line 3—3 of Fig. 1.

Fig. 4 is an enlarged section taken on the line 2—2 with parts broken away and removed.

Fig. 5 is illustrative of a group of disassembled parts of a modified form of article consisting of an illuminated star.

In Figs. 1 to 4, inclusive, there is shown a hollow three dimension article formed of translucent thermoplastic sheet material of cellulose derivative, and consisting of two separable mating sec-

2

tions. One section is formed of such material with a decorative rim 10 illustrated as having the configuration of a holly wreath. Said rim is curved outwardly in cross section to substantially the contour of a holly wreath. The outer periphery of the section terminates in an outwardly extending flange 11 and the inner periphery merges into an intermediate wall portion 12. Formed in the intermediate wall portion 12 there is a decorative enlargement 13, herein shown in the shape of a half section of a Christmas bell.

A mating section is similarly formed with the annular rim 14 surrounded by the flange 15 adapted to mate with and abut the flange 11. An intermediate wall portion 16 is formed within the rim and embraces the half section 17 of the decorative bell.

The two sections are so formed that when their flanges 11 and 15 are brought into abutment the intermediate wall portions 12 and 16 are in spaced relation to provide a light passage therebetween. The bell sections 13, 17 are formed to extend in opposed mating relation such as when the sections are assembled the bell will take on its natural shape to house therein a light source as indicated by the lamp 18 mounted in the socket 19 and having a conducting cord 20. The lamp socket is clamped by a wire clamping ring 21 supported at its opposite ends by a pair of inner and outer supporting rings 21b.

For packing and shipping the article the opposed sections in their disassembled relation may be nested one within the other. In assembling the sections, upon the flanges 11 and 15 being brought into abutment, wire forms 22 and 23 are seated about their respective flanges 11 and 15 and are rigidly clamped together by a series of detachable C-shaped spring clamps 24 adapted to be snapped over the wire forms at spaced intervals thereabout. Through the medium of the wire forms seating upon the flanges and removably clamped to each other by the clamps 24 the sections are firmly held together in their assembled relation.

By forming the intermediate wall portions 12 and 16 to a less depth than the flanges they are retained in spaced relation to provide an annular passage surrounding the light source 18 through which the light rays therefrom are free to pass into and be diffused about the decorative rims 10 and 14 for illuminating them, as well as the central decorative enlargements 13, 17.

In the exploded view of the modified form of article shown in Fig. 5, for purposes of illustration there is shown an illuminated star similarly

formed of two mating sections 110 and 114 surrounded by outwardly extending flanges 111 and 115, the central portions 113, 117, being spaced apart to receive a light source in the form of a bulb therebetween, said bulb being carried by a socket 120 formed in the central enlargement 117. For seating upon the flange 111 of the section 110 there is provided a wire form 122 conforming in shape to said flange, and for seating upon the flange 115 there is provided a corresponding wire ring 123. Said forms are clamped together when seated on their respective flanges and with the flanges of the respective sections in abutment by the spring clips 124.

Whereas there has been herein particularly described illuminated Christmas ornaments of molded thermoplastic sheet material, the article may take any desired form or be applied to any desired use such as a dress form, sign, or like articles of hollow three dimension structure with or without illumination wherein the structure comprises a pair of opposed mating sections with abutting peripheral flanges about which detachable wire forms are seated and secured by a series of removable clamps.

Wherein it may be desirable to mount such decorative article on a wall or surface so that only one side is exposed to view, then in that event only one of the sections need be preformed with the decorative contours; whereas the opposed section may be flat and unformed so as to lie against the supporting surface. However, the article would still maintain its three dimensional form with one surface in relief and spaced from the flat surface, the two sections being similarly assembled and secured by the forms as above described.

The invention claimed is:

1. A surface illuminated article comprising a pair of opposed and mating sections of translucent sheet material, each section being preformed to provide a decorative rim curved in cross section, the outer periphery of each section terminating in mating outwardly extending flanges and the inner periphery merging into an intermediate wall portion of less depth, a metal form removably mounted about the rim and seatable on the flange of each section, a series of spaced clamps engageable over said

forms upon said sections being assembled with their respective flanges abutting and with said wall portions in opposed spaced relation, an outwardly formed decorative enlargement in each wall, and an illuminating element mounted within said enlargements adapted for illumination thereof and dissemination of light rays through the space intermediate said wall portions to the said rims.

2. A surface illuminated article comprising a pair of opposed and mating sections of translucent sheet material, at least one of said sections being preformed to provide a decorative rim curved in cross section, the outer periphery of said rim terminating in an outwardly extending flange and the inner periphery merging into an intermediate wall portion of less depth, said flange being adapted to seat against the peripheral portion of the other said mating section, a form removably seatable on said flange, a conforming form seatable about the outer portion of the said other said section, a series of spaced clamps engageable over said forms upon said sections being assembled with their respective flanges and peripheral portions abutting and with their inner portions in opposed spaced relation, an outwardly formed decorative enlargement in the wall portion of said preformed section, and an illuminating element mounted within said enlargement adapted for illumination thereof and dissemination of light rays through the space intermediate the inner portions of said sections for illumination of the decorative rim on said preformed section.
